UNITED STATES PATENT OFFICE.

CALLO D. FAHRNEY, OF MILWAUKEE, WISCONSIN.

STREET-CLEANER.

1,033,164.

Specification of Letters Patent. Patented July 23, 1912.

Application filed February 2, 1911. Serial No. 606,145.

To all whom it may concern:

Be it known that I, CALLO D. FAHRNEY, a citizen of the United States, and resident of Milwaukee, in the county of Milwaukee and State of Wisconsin, have invented certain new and useful Improvements in Street-Cleaners; and I do hereby declare that the following is a full, clear, and exact description thereof.

10 My invention has for its object to provide a simple, effective and durable street cleaner, the construction and arrangement being such that a suction chamber is formed between a forward pliable roller and rear cylindrical brush, the suction chamber being practically closed upon three sides, whereby dust, dirt or other foreign matter is drawn through the cylindrical brush by a suitable suction power and collected in a settling 20 chamber.

Another object of my invention is to provide means whereby a maximum suction is obtained in proportion to the power applied, this advantageous result being primarily accomplished by disposing the cylindrical brush at an angle to the surface to which it is applied. Thus dust or dirt displaced by the brush will, by deflection, be caused to accumulate at one end of the 30 suction trough, which trough, as shown, is triangular in elevation with the suction pipe disposed at the base of said triangle, it being understood that the flexible roller is arranged parallel to the surface upon which it travels and normally serves as a rolling wall whereby the front of the suction chamber is practically hermetically sealed.

Another object of my invention is to provide a simple and effective trap mechanism 40 that is interposed within the suction pipe conduit whereby the dust or dirt and other foreign substances that may accumulate upon a pavement are collected, by which arrangement all foreign matter is trapped prior to reaching the fan, thus increasing the life and efficiency of the same.

Another object of my invention is to provide a valve-controlled nozzle in connection with the exhaust of the fan, whereby air 50 may be discharged if desired rearwardly of the cylindrical brush to assist the same in performing its cleaning functions; in which instance a complete circulation of air can be maintained from the fan through the 55 brush and suction pipes back to said fan.

In some instances where the blast is employed and the conditions warrant the cylindrical brush may be lifted entirely from the surface to be cleaned and the air circulation in this case depended upon entirely 60 for cleaning purposes, but it is preferable to utilize the stiff bristles of the cylindrical brush to loosen the dirt in most cases where the blast is used, the said blast being relied upon solely for blowing the dust forwardly 65 in the suction cleaner.

With the above and other minor objects in view my invention consists in certain peculiarities of construction and combination of parts as hereinafter fully set forth with 70 reference to the accompanying drawings and subsequently claimed.

In the drawings Figure 1 represents a side elevation of a street sweeping vehicle embodying the features of my invention 75 with parts broken away and parts in section to more clearly illustrate structural features; Fig. 2, a detailed plan view of the suction trough and its connected mechanism, with parts broken away and parts in section 80 to more clearly show certain structural features; Fig. 3, a detailed face view of the same looking toward the suction side thereof; Fig. 4, a transverse section of the suction mechanism, the section being taken 85 through the central portion of the suction chamber. Fig. 5, a detailed elevation of a flexible roller employed in connection with my street cleaning mechanism, the elevation being partly broken away and in section to more clearly show certain details of construction, and Fig. 6, a cross-section of the same, the section being indicated by line 90 6-6 of Fig. 5.

Referring by characters to the drawings, 95 1 indicates the truck frame provided with the usual front and rear wheels 2, it being understood that said truck, if desired, may be motor driven, although the same is illustrated as being equipped as a draft vehicle. 100

Centered to the truck frame 1 are rack arms 3, 3^a, the free ends of which carry struts 4, into the forward ends of which struts are journaled the ends of a pliable roller 5 which is adapted to impinge against 105 the surface to be cleaned and, owing to pressure upon said surface, the said roller is flattened at its contact point as shown, whereby an effective air seal at this point is insured. A shaft 6 is journaled in the 110

2
rear ends of the struts, the same being obliquely disposed with relation to the axis of the flexible roller. Secured to the shaft 6 is a cylindrical bristle brush 7 of any desired type, the brush being positively rotated in the direction as indicated by the arrow by chain and sprocket gear connection 8 between the brush shaft and fulcrum point of the rock arm 3^a, there being a second drive chain 8^a that serves as a gear connection between the rock arm fulcrum point and a motor 9, which motor is mounted upon the truck frame.

The gear drive from the motor to cylindrical brush just described forms no part of my invention, it being understood that any gear permitting oscillation of said brush may be employed.

As it is desirable in some instances to positively raise or lower the cylindrical brush, I have shown a spindle 10 that is in link connection with the lever that forms part of the rock arm 3^a. The spindle is provided with a hand wheel 11 at its upper end that is in threaded connection with the spindle whereby the same may be raised or lowered within a keeper block 12, the hand wheel being held to the keeper block by means of a finger carried thereby, which finger engages an annular recess in the hub of said hand wheel.

The forward rock arm 3 which controls the flexible roller is provided with an adjusting mechanism similar to that just described in connection with rock-arm 3^a, the spindle 10^a, in this instance, being provided with a hand-wheel 11^a. By this arrangement traction of the flexible roller may be increased or diminished by operating the hand-wheel 11^a, or, in case the machine is being transported, both hand-wheels may be manipulated to cause a lift of the entire suction mechanism from the ground.

Secured to the parallel struts 4 is a circular housing 13 that extends about the cylindrical brush, terminating at a predetermined distance from the surface upon which said brush rests. The inner edge of the housing between the roller and brush serves as a support for a triangular shaped cover-board 14, the side edges of which parallel the adjacent edges of the roller and brush as best shown in Fig. 2, the cover-board being also supported upon the struts 4 and constituting an extension of the hood. Interposed between the parallel edges of the cover-board and flexible roller is a rotatory spindle 15, one edge of which spindle is arranged to closely fit the edge of the cover-board, its opposite edge impinging against the roller, whereby a tight joint is formed between said roller and cover-board edge, the spindle, in connection with the cover-board, constituting a rolling joint.

35 The opposite or oblique edge of the cover-

board parallels the adjacent edge of the cylindrical brush and forms an open throat between the inner face of the cover-board and surface to be cleaned. The narrow end of the cover-board is also provided with an apron 16 that extends downwardly in juxtaposition to the surface to be cleaned.

The wide end of the cover-board is closed by a suction shoe 17, which suction-shoe is hinged to the adjacent strut 4 and extends across from the flexible roller to the brush, one face thereof being arranged to impinge against the cover-board edge. This shoe is adapted to slide upon the ground or surface to be cleaned and is provided with a mouth 18 that communicates with the suction chamber formed by the cover-board and its connected mechanism. The suction shoe terminates with an upwardly extended neck that is connected to a suction tube 19 by a flexible diaphragm 20, whereby the suction-shoe is permitted to rise and fall to accommodate its lower face to uneven surfaces, the rear end of the suction-shoe being provided with a hinged gate 17^a for the purpose of permitting large bodies that cannot be lifted by the suction force to escape.

The suction tube 19 is secured to the cover-board and extends upwardly to a centrifugal receiver or closed trap 21, the suction tube being provided with a flexible section between the vehicle frame and suction chamber to permit rise and fall of the latter. The suction tube enters the trap at a tangent, whereby a cyclonic action of the air is maintained, a second section 22 of the suction tube being centrally disposed and extending into the trap where it terminates with a bell mouth, as shown in Fig. 1. The second suction tube communicates with a fan 23 that is in belt connection with the motor 9, the same constituting a vacuum producer. The discharge mouth of the fan is provided with a valve-controlled duct 24, which has one branch 25 terminating rearwardly of the cylindrical brush, the mouth, as shown, being extended across the entire width of the brush and also communicating with the narrow end of the suction chamber as clearly shown in Fig. 2.

By the arrangement of valve-controlled duct 24 and its branch 25, it is apparent that should the valve be swung across the branch-pipe 25, that the air from the fan will be exhausted through the vent nozzle 25' which communicates with the duct 24 and is controlled by its valve. Should said valve be moved to the position shown in Fig. 1 of the drawings, the exhausting air from the fan would be discharged upon the surface cleaned in the direction indicated by the arrows, whereby the dirt will be blown into the suction chamber while the rotary brush, can, if desired, be utilized to loosen said dirt. In either case the dirt will be thrown for-

ward in the direction indicated by the arrows into the suction chamber and, owing to the angular disposition of the brush, the said dirt will accumulate in the wide end of said chamber, the brush having a tendency to throw the dirt into the mouth of the suction-shoe. The suction caused by the fan will thus lift the accumulated dirt and other foreign matter from the shoe up through the suction-pipe 19, the same being discharged into the trap. The cyclonic action of the air in said trap will cause the dust or other foreign substance collected therein to settle or drop downward into a receiving hopper 26, the inlet and discharge openings of which hopper are provided with valves 27, 27^a, respectively. By this arrangement, valve 27 being opened and the valve 27^a controlling the discharge opening of the hopper being closed, the dirt will be confined within said hopper and when it is desired to empty the same, a bag or other convenient receiver may be adjusted to the discharge mouth of the receiving hopper and by first closing valve 27 and thereafter opening valve 27^a, the contents of the receiving hopper can be readily discharged into the bag without disturbing the action of the air circulating system.

Referring to Fig. 5 of the drawings, the flexible roller 5 is formed as shown with a solid core 5' about which core is spirally wound a pneumatic tube 5'', which tube is inflated through a nipple 5'''. The coiled tube is covered with a flexible cylindrical jacket 5'''' as shown, the jacket being secured to the ends of the core 5'. By this construction it will be seen that said roller is provided with sufficient resiliency, whereby the weight exerted upon the same will cause it to flatten incidental to its rotation upon the surface to be cleaned, and thus maintain a practically air-tight joint at this point.

Particular attention is called to the fact that the suction chamber is open at its rear end, whereby the dust and dirt freed by the brush may be drawn therethrough and delivered to the receiving hopper, the forward wall of the suction chamber comprising a flexible rotary roller, whereby friction is eliminated and a practically air-tight joint insured. Thus the forward flexible roller working in conjunction with the driven cylindrical brush, the action of which throws the dirt forward into the suction chamber, will insure cleaning in a positive manner with the least expenditure of power, this result being particularly due to the fact that the cylindrical brush is obliquely disposed for the purpose stated.

I claim:

1. A cleaner comprising a truck-supported forwardly disposed flexible roller, a driven cylindrical brush spaced rearwardly of the roller, a housing extending partly over the

brush having one edge forming a tight joint in connection with the adjacent roller edge, end closures for the housing whereby a chamber is formed, and a suction-pipe connected to the chamber.

2. A cleaner comprising a truck-supported forwardly disposed flexible roller, a driven cylindrical brush rearwardly of the roller, a housing extending partly over the brush having one edge terminating adjacent to said roller, a rotary spindle interposed between the roller and adjacent edge of the housing, whereby a tight joint is formed therebetween, closures for the housing ends whereby a chamber is formed between the roller and brush, and a suction pipe in connection with the chamber.

3. A cleaner comprising a truck-supported forwardly disposed flexible roller, a driven cylindrical brush spaced rearwardly of the roller, struts connecting the brush and roller, a housing extending partly over the brush having one edge forming a tight joint in connection with the adjacent roller edge, whereby a chamber is formed between said brush and roller, a suction pipe in communication with the chamber, and a blast-pipe disposed rearwardly of the cylindrical brush.

4. A cleaner comprising a truck-supported forwardly disposed flexible roller, a truck-supported driven cylindrical brush spaced rearwardly of the roller and obliquely to the axis of the same, a housing extending partly over the brush having one edge forming a tight joint in connection with the adjacent roller edge, end closures for the housing whereby a chamber is formed between the roller and brush, and a suction pipe in communication with that end of the chamber of greatest width.

5. A cleaner comprising a truck-supported forwardly disposed flexible roller, a truck-supported driven cylindrical brush disposed rearwardly of the roller and obliquely to the axis thereof, a housing for the brush terminating at a predetermined distance from the bottom of said brush, a triangularly-shaped cover-board extending from the housing, one edge of which forms a tight joint in connection with the roller, the cover-board forming the top wall of a triangularly shaped suction chamber, and a suction pipe in connection with the chamber located at the wide end of the triangularly shaped cover-board.

6. A cleaner comprising a truck-supported forwardly disposed flexible roller, a truck-supported driven cylindrical brush disposed rearwardly of the roller and obliquely to the axis thereof, a housing for the brush terminating at a predetermined distance from the bottom of said brush, a triangularly shaped cover-board extending from the housing, one edge of which is

adapted to form a tight joint in connection with the roller, the cover-board forming the top wall of a triangularly shaped suction chamber, and a suction-shoe in yieldable connection with the wide end of the suction chamber.

7. A cleaner comprising a truck-supported forwardly disposed flexible roller, a truck-supported driven cylindrical brush disposed rearwardly of the roller and obliquely to the axis thereof, a housing for the brush terminating at a predetermined distance from the bottom of said brush, a triangularly shaped cover-board extending from the housing one edge of which is adapted to form a tight joint in connection with the roller, the cover-board forming the top wall of a suction chamber, a suction-shoe in adjustable engagement with the wide end of the triangularly shaped suction chamber, a suction pipe having one end in flexible connection with the suction-shoe, and a vacuum producing mechanism in connection with the opposite end of the suction pipe.

8. A traveling cleaner comprising a chamber closed at its front end and sides and having an obliquely disposed open rear end, the front end of the chamber being disposed at an approximately right angle to the direction of its travel, a rotary brush set parallel with the oblique open rear end of the chamber and arranged to oppose the same, means for imparting rotary drive to the brush in the same direction as that traveled by the cleaner and a vacuum producer in connection with the long side of the chamber, the vacuum producer being provided with a suction mouth that is disposed transversely of the chamber.

9. A traveling cleaner comprising a chamber formed with a flexible front wall and side closures and having an obliquely disposed open rear end, the front wall of the chamber being disposed at an approximately right angle to the direction of its travel, a brush set parallel with the oblique open rear end of the chamber and arranged to oppose same, whereby one end of said brush is advanced forwardly, and a suction shoe in communication with the long side of the chamber, the suction shoe being provided with a suction mouth that is disposed transversely of said chamber.

10. A traveling cleaner comprising a chamber formed with a flexible front wall and side closures and having an obliquely disposed open rear end, the front wall of the chamber being disposed at an approximately right angle to the direction of its travel, a brush set parallel with the oblique open rear end of the chamber and arranged to oppose same, whereby one end of said brush is advanced forwardly, and a suction shoe in communication with the long side of the chamber, the suction shoe being provided

with a suction mouth that is disposed transversely of said chamber, and having a gate controlled rear open end.

11. A cleaner comprising a chamber formed with a flexible front wall and short and long side closures and having an obliquely disposed open rear end, the front wall of the chamber being disposed at an approximately right angle to the direction of its travel, a brush closure for the rear oblique open end of the chamber, a blast pipe having mouths arranged respectively to discharge into the short side of the chamber and against the rear edge of the brush, and a suction pipe having its mouth in communication with the long side of the chamber, the suction and blast pipe connections with said chamber causing a cross current of air therethrough.

12. A cleaner comprising a chamber formed with a flexible front wall and short and long side closures and having an obliquely disposed open rear end, the front wall of the chamber being disposed at an approximately right angle to the direction of its travel, a brush closure for the rear oblique open end of the chamber, a blast pipe having its discharge mouth disposed rearwardly of the brush whereby air is discharged upon the surface to be cleaned, adjacent to the point the brush engages said surface, and a suction shoe in communication with the long side of said chamber, the mouth of the suction shoe being disposed transversely of the aforesaid chamber, just forward of its brush closure.

13. A traveling cleaner comprising a chamber formed with a flexible front closure wall and having an obliquely disposed open end, the front wall being disposed at an approximately right angle to the direction of its travel, a rotary brush set parallel with the oblique open end of the chamber and arranged to oppose the same, whereby one end of the brush is in advance of the other end, means for imparting drive to the brush in the same direction as that traveled by the cleaner, a permanent closure wall for the narrow side of the chamber, and an oscillatory suction shoe fitted to the long side of the chamber constituting a closure therefor, the suction shoe being provided with a mouth disposed transversely of said chamber, whereby sweepings that are deflected into the long end of the aforesaid chamber are drawn through said suction shoe.

14. A traveling cleaner comprising a brush disposed at an angle to the direction of its travel, and a vacuum producer in juxtaposition to the following end of the brush whereby a pocket is formed at said end, the vacuum producer being provided with a suction mouth that is disposed transversely of the brush, whereby accumulated refuse at said following end of the brush will flow

into the mouth of the vacuum producer independent of suction force.

15. A cleaner comprising a yieldable front closure, a brush disposed rearwardly of the front closure and at an angle to the direction of travel, an end shoe extending from the front closure to the following end of the brush whereby a pocket is formed at said end, and a suction pipe in communication with the shoe the shoe being provided with a suction mouth that is disposed transversely of the brush, whereby accumulated refuse at the following end of the aforesaid brush will flow into the shoe mouth independent of suction force.

16. A traveling cleaner comprising a chamber closed at its front end and having an obliquely disposed open rear end, a brush set parallel with the oblique open end of the chamber and arranged to oppose the same, a yieldable shoe having a mouth in communication with the chamber at the following end of said brush, and a vacuum producer in communication with the shoe.

25 17. In a traveling cleaner, the combination with an obliquely disposed driven cylindrical sweeping element, of a forwardly moving oscillatory suction shoe of elongated contour in horizontal cross section, the side wall 30 of the shoe adjacent to the said brush being

cut away to a predetermined extent to provide a lateral mouth adjacent to the surface to be cleaned, the same being adapted to receive the concentrated and agitated sweepings from the said sweeping element, the 35 said shoe having its outside wall extending to the surface to be cleaned and thereby serving as a confining wall for the agitated sweepings from the sweeping element and as a runner for the suction shoe.

40* 18. A traveling cleaner comprising a chamber formed with a flexible front wall and having an obliquely disposed open rear end, a brush set parallel with the oblique open rear end of the chamber and arranged 45 to oppose the same, whereby one end of said brush is advanced forwardly, and a suction shoe in communication with the long side of the chamber, the suction shoe being provided with a suction mouth that is disposed 50 transversely of said chamber.

In testimony that I claim the foregoing I have hereunto set my hand at Milwaukee in the county of Milwaukee and State of Wisconsin in the presence of two witnesses.
